TANK FOR VEHICLES

Benjamin D. Barton, Battle Creek, Mich., assignor
to American-Marsh Pumps, Inc., Battle Creek,
Mich.

Application January 10, 1942, Serial No. 426,297

2 Claims. (Cl. 220—86)

This invention relates to improvements in tanks for vehicles.

It is now quite general practice in fire engines and the like, even those used in cities, to provide a tank for carrying a substantial volume of water, and in fire engines for rural use or beyond the reach of water mains, this is still more important. In many instances fire engines are provided with water tanks in lieu of chemical fire extinguishers. In such equipment, the vehicle frequently is positioned on uneven surfaces, or in going up or down hills or in similar situations, there is a tendency for the water to run out through the filling opening. To prevent this, the filling means is frequently in the form of a riser, rising a substantial distance above the top of the tank and this adds to the labor and difficulty in filling the tank. Once at the scene of the fire where water mains are not available, the tanks are kept filled with bucket brigades or the like. Therefore the filling is an important factor.

The main objects of my invention are:

First, to provide an improved vehicle tank of the character described which may be filled with a hose where considerable supplies of water under pressure are available, or by means of buckets.

Second, to provide a tank of the class described having a filling chamber which permits the rapid emptying of a pail or water bucket and without undue loss of water.

Further objects and advantages pertaining to details and economies of construction and operation will appear from the description to follow. The invention is defined in the claims. A preferred embodiment of my invention is illustrated in the accompanying drawing, in which:

Fig. 1 is a fragmentary view partially in longitudinal section of a fire engine structure embodying the features of my invention.

Fig. 2 is a fragmentary top plan partially broken away and in horizontal section, further showing certain of the structural details.

Fig. 3 is an enlarged fragmentary view in vertical longitudinal section with the filling chamber tank shown in open position by full lines and in closed position by dotted lines and further illustrating the action of the spring actuated toggle for holding the cover in open and in closed position.

In the accompanying drawing, 1 represents the body of a fire truck and 2 a hand rail thereof. A tank 3 designed to hold a substantial volume of water is built into the truck. 1 provides in

connection with the tank, a filling chamber 4. The inner wall 5 of this chamber is set into the tank, the purpose of this being to extend the rear end of the tank as far as possible and still leave suitable foot room on the platform 6. The outer portion 7 of the filling chamber projects from the tank above the platform. The filling chamber is connected with a tank through the valve casing 8 which is in the form of a T-fitting, one arm of the valve casing being secured to the inner wall 5 of the filling chamber so that the valve casing is positioned within the filling chamber.

An upwardly closing flap valve 9 permits the water to flow from the filling chamber into the tank but prevents its return. The plug 10 may be removed to provide a filling opening in the valve casing in which the end of a hose may be inserted. This provides a rapid and easy way of filling the tank at the station or headquarters and also the tank may be kept filled by this means in the event a supply of water under pressure is available.

It frequently happens that there are locations provided with water systems which do not have fire hydrants. The fire engine draws its water from the tank. The fire engines are sometimes designed to serve as boosters on water systems.

In many instances water under pressure is not available and in such cases a so-called bucket brigade is formed to supply water to the tank. The buckets or pails may be poured into the filling chamber which is provided with a cover 11 hinged at 12 to be swung upwardly to the erected position shown in Fig. 3, in which position it constitutes a splash wall or board which drains into the filling chamber. The cover 11 is yieldingly held in its open and also in its closed position by means of a spring pressed toggle mechanism comprising the arm 13 depending from the cover adjacent its hinge and the link 14 which is pivoted at 15 to the arm and slidably and rockably supported by the bracket 16, the link being arranged through hole 17 in the bracket. The spring 18 is supported at one end by the bracket and engages the thrust pin 19 on the link.

It will be noted that as the cover is opened and closed the pivot 15 swings past the plane through the pivot of the cover and the point of engagement of the link with the bracket, thus providing a snap action for the toggle.

With this simple arrangement of parts, I provide a filling means which greatly aids in the rapid filling or supplying water to the tank by

the bucket brigade method and also a means which prevents loss of water as a result of the tank being in inclined position or through splashing.

I have not illustrated or described certain improvements or adaptations which I contemplate, as it is believed that this disclosure will enable those skilled in the art to embody or adapt my improvements as may be desired.

Having thus described my invention, what I claim as new and desire to secure by Letters Patent is:

1. In a structure of the class described, the combination with a tank of a filling chamber at one end of said tank, certain walls of said filling chamber being partly within the tank, a T-shaped valve casing mounted on the inner wall of said filling chamber to deliver to said tank and provided with an outwardly closing check valve and having a filling opening at the rear of the check valve provided with a closure plug whereby the tank may be filled with a hose or through the said filling chamber, a pivoted cover

for said filling chamber adapted when open to provide a splash wall, and a toggle device for holding said cover in open or closed position comprising an arm on said cover, a link pivotally connected to said arm and slidably engaged with a bracket within said filling chamber, and a spring arranged on said link under compression and acting to hold the cover in either its open or closed position.

5 2. In a structure of the class described, the combination with a tank, of a filling chamber at one end of said tank, certain walls of said filling chamber being partly within the tank, a T-shaped valve casing mounted on the inner wall of said filling chamber to deliver to said tank and provided with an outwardly closing check valve and having a filling opening at the rear of the check valve whereby the tank may be filled through the said filling chamber, and a pivoted cover for said filling chamber adapted 10 when open to provide a splash wall.

BENJAMIN D. BARTON.
